[57] CLAIM

The ornamental design for a portable pneumatic sweeper, as shown and described.

DESCRIPTION

FIG. 1 is a right side elevational view of a portable pneumatic sweeper showing our new design;

FIG. 2 is a left side elevational view thereof;

FIG. 3 is a front elevational view thereof;

FIG. 4 is a rear elevational view thereof;

FIG. 5 is a top plan view thereof; and

FIG. 6 is a perspective view thereof.

Our new design is intended for removing leaves and similar trash from surfaces by a stream of blown air. The undisclosed bottom is substantially planar and unornamented.
